FIG. 1 is a front, perspective view of a soft sole footwear with adjustable plantar arch support showing my new design, positioned on both a right foot and a left foot of a user that is shown in broken lines;

FIG. 2 is a left view thereof, positioned on a left foot of a user;

FIG. 3 is a left view thereof, positioned on a right foot of a user;

FIG. 4 is a rear view thereof, positioned on each foot of a user;

FIG. 5 is a bottom view thereof, positioned on both a right foot and a left foot of a user that is shown in broken lines; and,

FIG. 6 is a rear view thereof, shown in an unused position. The broken lines showing of portions of the soft sole footwear with adjustable plantar arch support are included for the purpose of illustrating environmental structure and form no part of the claimed design. All surfaces not shown form no part of the claimed design.
